[57] ABSTRACT

One of the members has a track raised thereon which is equipped with arcuate surfaces on opposite sides thereof, that are concentric with the rotational axis of the members, and joined to one another at the corresponding ends thereof. The other member extends transversely of the track between the aforesaid opposite sides thereof, and has a wheel rotatably carried thereon, the rotational axis of which is parallel to the axis of the members but transversely shiftable in relation thereto. The wheel is yieldably biased into engagement with the surface of the track, on each side thereof, and the members are rotated in relation to one another by driving the wheel in one rotational direction thereof, so as to cause either the wheel or the track to undergo rotation about the axis of the members, there being yieldable biasing means for retaining the wheel in engagement with the track as it crosses the junctures between the surfaces at their ends.

MEANS FOR OSCILLATING ONE OF A PAIR OF RELATIVELY ROTATABLE MEMBERS

OBJECTS OF THE INVENTION

One object of the present invention is to provide a means and technique for converting the motor-driven unidirectional angular motion of a rotatable input member, into reciprocable angular motion on the part of one or the other of a pair of relatively rotatable output members. Another object is to provide a means and technique of this nature wherein the relative angular displacement of the output members can be varied between an arc of little more than zero degrees, and an arc approaching 360 degrees. Still another object is to provide a means and technique of this nature wherein the relative reciprocable motion of the output members can be reversed, almost instantly, by reversing the angular direction of the input member, as for example, by reversing the direction of the motor which operates to drive the same. A further object is to provide a means and technique of this nature whereby the relatively rotatable output members can be spaced narrowly apart from one another, and the input member can be accommodated in the space therebetween to produce a highly compact oscillatory arrangement. A still further object is to provide a means and technique of this nature whereby the arrangement is assembled and constructed from relatively few components other than the input and output members themselves. Other objects include the provision of a means and technique of this nature whereby the few additional components are commonly relatively inexpensive components such as springs and/or simple lever-mounted roller assemblies; and all of the components in the arrangement are capable of extended lives, even under conditions of continuous operation, because of the small number of wear surfaces, and the low operating speeds which may be employed. Still further objects will become apparent from the description of the invention which follows hereafter.

SUMMARY OF THE INVENTION

These objects and advantages are realized by a means and technique of our invention wherein one of the relatively rotatable output members has a track raised thereon which is equipped with arcuate surfaces on opposite sides thereof, that are concentric with the rotational axis of the members and joined to one another at the corresponding ends thereof. The other member extends transversely of the track between the aforesaid sides thereof, and has a wheel rotatably carried thereon, the rotational axis of which is parallel to the axis of the members but transversely shiftable in relation thereto. The wheel is yieldably biased into engagement with the surface of the track, on each side thereof, and the members are rotated in relation to one another by driving the wheel in one rotational direction thereof, so as to cause either the wheel or the track to undergo rotation about the axis of the members, there being yieldable biasing means for retaining the wheel in engagement with the track as it crosses the junctures between the surfaces at their ends.

The wheel retainer means is displaceable against the bias thereof, in directions crosswise the axis of the members, and may be disposed on the relatively stationary member and engageable with the relatively rotatable member to load the wheel against the junctures

between the surfaces; or it may be disposed on the relatively rotatable member and engageable with the relatively stationary member for this purpose. For example, in certain of the presently preferred embodiments of the invention, the wheel retainer means is mounted on the track bearing member and engageable with either the wheel or the wheel bearing member, to load the wheel against the junctures between the surfaces. In other such embodiments, it is mounted on the wheel bearing member and engageable with the track for this purpose. In these latter embodiments, moreover, the retainer means is also operable to yieldably bias the wheel into engagement with the surfaces of the track.

The wheel may be shiftable along a radial line through the axis of the members, or it may be shiftable crosswise of such a line. For example, the wheel may be outriggered on a carriage which is shiftable along the line; or it may be outriggered on a leaf spring which is disposed crosswise of the line, and has the wheel adjacent the outlying end thereof. Preferably, the spring is cantilevered from the other member at a point on the side of the track opposite from the rotational axis of the members, and extends to a point between the axis and the track, the wheel being carried on the spring adjacent the latter point.

Also, it is preferred that the other member take the form of an arm, acting either as a gantry rail for the carriage, or as an outrigger boom for the leaf spring. In certain embodiments, moreover, the boom and the spring may be combined as a V-shaped leaf spring, cantilevered by one end from a shaft, with the bight thereof disposed at a point on the side of the rail opposite from the shaft.

The track is preferably defined by a rail which is upstanding on the one member. The rail may have a single-walled cross section, the opposite sides of which form the surfaces of the track; or it may have a spaced, double-walled cross section, the relatively remote sides of which form the surfaces of the track.

In the single-walled construction, the wheel retainer means may include a yieldably biased bumper element adjacent each juncture of the rail. The bumper element may take the form of a leaf spring which is anchored to the one member at one end, and disposed adjacent the juncture of the rail to engage the other member when the wheel approaches the juncture; or the bumper element may take the form of a roller which is rotatably mounted on a spring-loaded lever that is pivotally mounted on the one member to yieldably engage the roller with the juncture of the rail.

In the double-walled construction, the wheel retainer means may include a yieldably biased clamping wheel interposed between the walls of the rail.

BRIEF DESCRIPTION OF THE DRAWINGS

These features will be better understood by reference to the accompanying drawings which illustrate three of the presently preferred embodiments.

In the drawings,

FIG. 1 is a perspective view of the mechanism employed in one embodiment;

FIG. 2 is a plan view of this mechanism in one operational condition thereof;

FIG. 3 is a side elevational view of the mechanism in this condition;

FIG. 4 is a part cross-sectional view of the mechanism in this same condition;

FIG. 5 is another plan view of the mechanism illustrating both the other operating condition and the changeover of the mechanism from one condition to the other;

FIG. 6 is a perspective view of the mechanism employed in a second embodiment;

FIG. 7 is a schematic illustration of the means by which the mechanism undergoes a changeover of operating condition;

FIG. 8 is a similar illustration of a means by which the mechanism is safeguarded against slippage;

FIG. 9 is an elevational illustration of the latter means;

FIG. 10 is a perspective view of the mechanism employed in the third embodiment;

FIG. 11 is a part cross-sectional view of the mechanism;

FIG. 12 is a similar view of the mechanism at a different stage in its operation;

FIG. 13 is a part elevational view of the mechanism along the line 13—13 of FIG. 11; and

FIG. 14 is a part plan view of the mechanism along the line 14—14 of FIG. 11.

DESCRIPTION OF THE PREFERRED EMBODIMENTS

Referring to FIGS. 1-5 of the drawings, it will be seen that the mechanism in the first embodiment comprises a square-shaped plate 2 having an eccentrically located aperture 4 therein, and an arcuate rail 6 upstanding thereon about the center of the aperture. The rail 6 is spotwelded to the near edge of the plate 2 in FIG. 1, and in addition, is secured to the far corners of the plate by right angular brackets 8 which are attached to the rail slightly inboard from the bladed ends 10 thereof. The rail serves as a tracking surface for a wheeled, motor-driven crank device 12 which is erected upright in the aperture 4 and supportably journaled within a roller bearing 14 that is bolt-clamped to the rim of the aperture 4 between the plate 2 and a collar 16 superposed thereon. The crank device 12 comprises a flat, horizontally disposed crank arm 18, the inner end 18' of which is bifurcated and pinch-screw-clamped onto a pintle-like arbor 20 for the same, constructed from a threaded pipe section having a pair of nuts 22 thereon which serve to locate the arbor in the bearing 14. The arm 18 extends to a point outside the rail 6, where there is an elongated leaf spring 24 secured to a right angular bracket 26 on the upper side of the outlying end thereof. The spring 24 is acutely re-entrantly angled to the arm in a vertical plane, so as to extend transversely of the rail to a point inside thereof. At this point, the spring has an apertured right angular bracket 30 attached to one side thereof, which in turn has a cylindrically apertured collar 28 seated on the horizontal leg thereof, to provide a saddle for an electric motor 32 which is mounted upright in the collar, with the shaft 34 thereof depending vertically through the aperture in the bracket, and carrying a vertically oriented, cylindrical wheel 36 thereon.

The crosswise disposition of the spring 24 with respect to the rail 6, is such that the wheel 36 is yieldably biased into engagement with the rail, whether the wheel is disposed inside or outside of the same. Thus, when the motor 32 is energized, the wheel 36 bears against the adjacent convex or concave surface 6' or 6'', respectively, of the rail, and tracks along the sur-

face from one end 10 thereof to the other. The tracking of the wheel causes the crank device 12 to rotate in turn about the axis of the arbor 20, there being, however, a pair of upright leaf springs 38 and 40 bracketed to the base plate 2, adjacent the ends 10 of the rail, which intercept the arm 18 as the wheel 36 approaches either end 10 of the rail. When the arm is so engaged, the wheel leaves the surface and, reacting to the bias of the spring 38 or 40, tracks onto and about the blade at 10 that end, until it eventually reverses its direction along the opposite surface of the rail. See FIG. 5 where the arm has abutted the spring 38 as the wheel approached the left-hand end of the rail after travelling along the concave surface 6'' thereof; or conversely, abuts the 15 spring 40 so as to reverse the course of the device in the opposite direction about the right-hand end of the rail, after the wheel has travelled along the convex surface 6' of the same.

The second embodiment also comprises an apertured square-shaped base plate 42 having an arcuate rail 44 upstanding thereon which is fixed to the plate about the center of the aperture 46 therein. In this instance, however, the plate and rail are rotatably journaled about a fixed shaft 48 which is equipped with a pair of spaced collars 50 and 52 for locating the plate 42 thereon. The shaft 48 has a round-bighted V-shaped leaf spring 54 cantilevered by one end therefrom, which crisscrosses above the rail 44 in such a fashion as to place the bight 54' of the same outside the rail, and the free-end 54'' of the same inside of the rail. This latter end 54'' is equipped with a laterally projecting flange or bracket 56 thereon, and a motor-driven wheel 58 is outriggered on the flange so as to remain engaged with the rail under the bias of the spring. When the wheel is rotated, the tracking action of the wheel causes the rail and plate to rotate about the shaft; and when the continued rotation of the same brings the approaching end of the rail to a point of coincidence with the wheel, the wheel engages one of a pair of rollers 60 which are rotatably mounted on the free-ends of a pair of spring-loaded levers 62 that are pivotally mounted in turn on the plate 42 to yieldably engage the rollers with the ends of the rail as in FIG. 6. The respective roller 60 engages the wheel and acts to maintain it on the rail, as the wheel crosses the juncture between the concave and convex surfaces thereof, the illustration of FIG. 7 illustrating the mode of this action, although in schematic terms only, since as indicated, the rail in fact travels in relation to the wheel, contrary to the illustration.

A pin 64 on the wheel assures that the wheel continuously tracks around the end of the rail, in that the pin will engage an upstanding pin 66 on the end of the rail as soon as slippage starts to occur.

In the third embodiment of FIGS. 10-14, the square-shaped base plate 68 has an arcuate, double-walled ribbon rail 70 upstanding thereon, the inside and outside walls of which, 72 and 74, respectively, are spaced apart from one another but joined to one another at the corresponding ends thereof by rounded bight sections 76. Superimposed about the center of the plate is a bearing 78 which has an upright shaft 80 rotatably journaled therein. Cantilevered from the top of the shaft is a crank-device 81 comprising a horizontally extending crank arm 82 which is flat and oriented in a vertical plane to form a gantry rail for a motor-driven tracking device 84 at the outlying end thereof. The tracking device 84 comprises a bracket-like carriage 86 which is

movably engaged on the arm 82 by means of three peripherally-grooved rollers 88 journaled to the back of the L-shaped bracket 90 thereof. The bracket forms a saddle for an electric motor 92 which is mounted upright thereon, with the shaft 94 thereof depending vertically through an aperture in the bracket 90, and carrying a vertically oriented cylindrical drive wheel 96 thereon. The wheel 96 is yieldably biased into engagement with the walls 72 and 74 of the ribbon rail 70, and retained on the rail at the bights 76 thereof, by means of a spring-loaded clamping wheel 98 which is disposed on the inside of the rail, between the walls thereof. The clamping wheel 98 is carried in a U-shaped, yoke-like bracket 100 which is journaled about the shaft 94 of the drive wheel 96, on a bearing 102, and comprised of a slotted L-shaped base portion 104, and a pair of spaced parallel arms 106 extending reentrantly therefrom. The spindle 108 of the clamping wheel 98 is trunnioned between the arms 106, and depends within the slot 110 of the base portion, to suspend the wheel 98 therebelow. To load the wheel 98 against the rail 70, a coiled spring 112 is caged between the upright wall 104' of the base portion 104 and a shoe 114 on the spindle 108. The spring 112 operates to bias the wheels 96 and 98 relatively toward one another, the carriage 86 meanwhile shifting lengthwise of the arm 82 to accommodate for the distance between the walls 72 and 74 of the rail, and the bracket 100 likewise swivelling about the shaft 94 of the wheel 96 to follow the travel of the wheels 96 and 98 from one wall to the other.

In lieu of an electric motor, other drive means may be employed, such as a pneumatic, hydraulic, or spring-driven motor. Likewise, other modifications and additions can be made in and to the invention without departing from the scope of the same as defined in the claims following.

What is claimed is:

1. In combination, a pair of relatively rotatable members, one of which members has an arcuate track raised thereon, the ends of which are spaced apart from one another and the relatively convex and concave surfaces of which are concentric with the rotational axis of the members and joined to one another at the ends of the track, and the other of which members extends transversely of the track between the surfaces thereof, and has a wheel rotatably carried thereon, the rotational axis of which wheel is parallel to the axis of the members but transversely shiftable in relation thereto, the wheel being yieldably biased into engagement with the track, and there being means for rotating the wheel about the axis thereof, to cause the wheel and the track to reciprocate in relation to one another, relatively about the axis of the members, and yieldable biasing means operative to retain the wheel in engagement with the track when the wheel reaches the respective ends of the track, whereby the wheel relatively traverses alternate surfaces of the track, and traverses from surface to surface across alternate junctures therebetween.

2. The combination according to claim 1 wherein the wheel retainer means is displaceable against the bias thereof, in directions crosswise the axis of the members, and is disposed on the relatively stationary member, and engageable with the relatively rotatable member to load the wheel against the junctures between the surfaces.

3. The combination according to claim 1 wherein the wheel retainer means is displaceable against the bias thereof, in directions crosswise the axis of the members, and is disposed on the relatively rotatable member, and engageable with the relatively stationary member to load the wheel against the junctures between the surfaces.

4. The combination according to claim 1 wherein the wheel retainer means is mounted on the track-bearing member, and engageable with either the wheel or the wheel bearing member to load the wheel against the junctures between the surfaces.

5. The combination according to claim 1 wherein the wheel retainer means is mounted on the wheel bearing member, and engageable with the track to load the wheel against the junctures between the surfaces.

6. The combination according to claim 5 wherein the wheel retainer means is also operable to yieldably bias the wheel into engagement with the surfaces of the track.

7. The combination according to claim 1 wherein the wheel is shiftable along a radial line through the axis of the members.

8. The combination according to claim 1 wherein the wheel is shiftable crosswise of a radial line through the axis of the members.

9. The combination according to claim 7 wherein the wheel is outriggered on a carriage which is shiftable along the line.

10. The combination according to claim 8 wherein the wheel is outriggered on a leaf spring which is disposed crosswise of the line and has the wheel adjacent the outlying end thereof.

11. The combination according to claim 10 wherein the spring is cantilevered from the other member at a point on the side of the track opposite from the rotational axis of the members, and extends to a point between the axis and the track, the wheel being carried on the spring adjacent the latter point.

12. The combination according to claim 9 wherein the other member takes the form of an arm, acting as a gantry rail for the carriage.

13. The combination according to claim 10 wherein the other member takes the form of an arm, acting as an outrigger boom for the leaf spring.

14. The combination according to claim 13 wherein the boom and the spring are combined as a V-shaped leaf spring, cantilevered by one end from a shaft, with the bight thereof disposed at a point on the side of the rail opposite from the shaft.

15. The combination according to claim 1 wherein the track is defined by a rail which is upstanding to the one member.

16. The combination according to claim 15 wherein the rail has a single-walled cross section, the opposite sides of which form the surfaces of the track.

17. The combination according to claim 15 wherein the rail has a spaced, double-walled cross section, the relatively remote sides of which form the surfaces of the track.

18. The combination according to claim 16 wherein the wheel retainer means includes a yieldably biased bumper element adjacent each juncture of the rail.

19. The combination according to claim 18 wherein the bumper element takes the form of a leaf spring which is anchored to the one member at one end, and disposed adjacent the juncture of the rail to engage the

other member when the wheel approaches the juncture.

20. The combination according to claim 18 wherein the bumper element takes the form of a roller which is rotatably mounted on a spring-loaded lever that is pivotally mounted on the one member to yieldably engage the roller with the juncture of the rail.

21. The combination according to claim 17 wherein the wheel retainer means includes a yieldably biased clamping wheel interposed between the walls of the rail.

22. In combination, a pair of relatively rotatable members, one of which members has a track raised thereon which is equipped with arcuate surfaces on opposite sides thereof, that are concentric with the rotational axis of the members, and joined to one another at the corresponding ends thereof, and the other of which members extends transversely of the track between the aforesaid opposite sides thereof, and has a wheel rotatably carried thereon, the rotational axis of which wheel is parallel to the axis of the members but transversely shiftable in relation thereto, the wheel being yieldably biased into engagement with the surface of the track on each side thereof, there being means for driving the wheel in one rotational direction thereof, to cause either the wheel or the track to undergo rotation about the axis of the members, and yieldable biasing means for retaining the wheel in engagement with the track as the wheel crosses the junctures between the surfaces at their ends, the wheel being outriggered on a leaf spring which is disposed crosswise of a radial line through the axis of the mem-

bers, and which is cantilevered from the other member at a point on the side of the track opposite from the rotational axis of the members, and extends to a point between the axis and the track, the wheel being carried on the spring adjacent the latter point.

23. In combination, a pair of relatively rotatable members, one of which members has a track raised thereon which is equipped with arcuate surfaces on opposite sides thereof, that are concentric with the rotational axis of the members, and joined to one another at the corresponding ends thereof, and the other of which members extends transversely of the track between the aforesaid opposite sides thereof, and has a wheel rotatably carried thereon, the rotational axis of which wheel is parallel to the axis of the members but transversely shiftable in relation thereto, the wheel being yieldably biased into engagement with the surface of the track of each side thereof, there being means for driving the wheel in one rotational direction thereof, to cause either the wheel or the track to undergo rotation about the axis of the members, and yieldable biasing means for retaining the wheel in engagement with the track as the wheel crosses the junctures between the surfaces at their ends, the wheel being outriggered on a V-shaped leaf spring which is cantilevered by one end from a shaft, with the bight thereof disposed at a point on the side of the track opposite from the shaft, and with the wheel carried adjacent the outlying end thereof.

24. The combination according to claim 1 wherein the wheel is frictionally engaged with the track.
